(57) **CLAIM**

The ornamental design for a digital microscope, as shown and described.

DESCRIPTION

FIG. 1 is a top, front and right side perspective view of a digital microscope showing my new design; FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 2;

FIG. 10 is a perspective view showing the digital microscope connected with a pair of probes in a state of use; and, FIG. 11 is another perspective view showing the digital microscope connected with another pair of probes in another state of use.

The evenly dashed broken lines in the drawings depict portions of the digital microscope which form no part of the claimed design.

The unevenly dashed broken lines in FIGS. 2 and 9 demarcate the enlarged view and form no part of the claimed design.

The additional broken lines in FIGS. 10 and 11 depict environmental subject matter and form no part of the claimed design.
